United States Patent Office

Des. 228,993
Patented Nov. 6, 1973

228,993

SHAVING EQUIPMENT HOLDER

William E. Jackson, 3933 Jan Ave.,
Tyler, Tex. 75701

Filed May 1, 1972, Ser. No. 249,486

Term of patent 14 years

Int. Cl. D6—06

U.S. Cl. D6—91

FIG. I

FIG. II

FIG. 1 is a top front perspective view of a shaving equipment holder showing my new design; and
FIG. 2 is a bottom rear perspective view thereof.

I claim:

The ornamental design for a shaving equipment holder, substantially as shown.
